MANUFACTURING COMPANY, OF SAME PLACE.

DESIGN FOR PRINTING-TYPE.

SPECIFICATION forming part of Design No. 15,502, dated October 28, 1884.

Application filed August 19, 1884. Term of patent 14 years.

To all whom it may concern:

Be it known that I, HENRY H. THORP, of the city of Cleveland, in the county of Cuyahoga and State of Ohio, have produced a new 5 and original Design for Printing - Types, of which the accompanying specimen or impression is an exact representation, and is made a part of this specification.

What I claim as my invention, and desire to secure by Letters Patent, is—

The design herein set forth for font of printing-types.

HENRY H. THORP.
